US00D854468S

(12) **United States Design Patent** (10) **Patent No.:** **US D854,468 S**
(45) **Date of Patent:** **** Jul. 23, 2019**

(54) **ENERGY ABSORPTION MEMBER**

- (71) Applicant: **SABIC Global Technologies B.V.**, Bergen op Zoom (NL)
- (72) Inventors: **Dinesh Munjurulimana**, Bangalore (IN); **Arunachala Parameshwara**, Bangalore (IN); **Venkatesha Narayanaswamy**, Bangalore (IN); **Dhanendra Nagwanshi**, Farmington Hills, MI (US); **Matthew M. Delaney**, Wixom, MI (US)
- (73) Assignee: **SABIC GLOBAL TECHNOLOGIES B.V.**, Bergen op Zoom (NL)

(**) Term: **15 Years**

(21) Appl. No.: **29/622,064**

(22) Filed: **Oct. 13, 2017**

(57) **CLAIM**

The ornamental design for an energy absorption member, as shown and described.

DESCRIPTION

FIG. 1 is a top, right, front perspective view of an energy absorption member according to an embodiment of our design;

FIG. 2 is a bottom, left, rear perspective view thereof; FIG. 3 is another top, right, front perspective view thereof; FIG. 4 is a top, left, rear perspective view thereof; FIG. 5 is a bottom, left, front perspective view thereof; FIG. 6 is a bottom, right, rear perspective view thereof; FIG. 7 is a front elevation view thereof; FIG. 8 is a rear elevation view thereof; FIG. 9 is a bottom plan view thereof; FIG. 10 is a top plan view thereof; FIG. 11 is a right side elevation view thereof; and, FIG. 12 is a left side elevation view thereof.

The broken lines in the drawings illustrate portions of the energy absorption member that form no part of the claimed design.

1 Claim, 6 Drawing Sheets
